(57) **CLAIM**

The ornamental design for an emergency electric power switch with terminal hood, as shown and described.

DESCRIPTION

1. Emergency electric power switch with terminal hood
Fig. 1.1 is a front, right, top perspective view of an emergency stop switch with terminal hood according to the present application;

Fig. 1.2 is a rear, left, top perspective view thereof;

Fig. 1.3 is a front view thereof;

Fig. 1.4 is a rear view thereof;

Fig. 1.5 is a left side view thereof;

Fig. 1.6 is a right side view thereof;

Fig. 1.7 is a top view thereof; and

Fig. 1.8 is a bottom view thereof.

The broken lines in the figures show portions of the emergency electric power switch with terminal hood that form no part of the claimed design.
